UNITED STATES PATENT OFFICE.

JONATHAN P. COLLETT, OF GREENVILLE, OHIO.

MAUSOLEUM.

1,115,284.

Specification of Letters Patent. Patented Oct. 27, 1914.

Application filed January 26, 1914. Serial No. 814,276.

To all whom it may concern:

Be it known that I, JONATHAN P. COLLETT, a citizen of the United States, residing at Greenville, in the county of Darke and State of Ohio, have invented a certain new and useful Improvement in Mausoleums, of which the following is a specification.

The object of this invention generally is to provide certain improvements in mausoleums for community use which render them more simple in construction and use and more sanitary than those heretofore proposed or in use.

Especial objects of the invention are to provide improved means for carrying off and disposing of obnoxious gases and seepage from sealed crypts and for preventing the escape of gases from sealed crypts to unsealed ones or into the main structure of the mausoleum.

The invention is embodied in the construction herein illustrated and described, the features of novelty being pointed out in the appended claims.

In the accompanying drawings forming part hereof—Figure 1 is a view in vertical section taken longitudinally of the crypts or catacombs and also showing in elevation the well into which seepage and gases flow. Fig. 2 is a view in vertical section taken transversely of the crypts or catacombs and also showing in vertical section the well into which the seepage and gases flow. Fig. 3 is a sectional detail on a larger scale to illustrate the frangible temporary closure of the seepage and gas outlet for the crypt. Fig. 4 is a detail in side view, partly in section on a larger scale, of the glass closure.

In the views 5 designates a suitable foundation upon which the main building is erected.

6 designates the outer wall and 7 the roof of the building.

The crypts or catacombs 8 are formed of cement in laterally connected tiers. Between the floor and the lowermost crypt is an air passage 9 and between the outer wall 6 and crypt structure is a vertical air passage 10 that opens near the roof. The passages 9 and 10 lead one into the other, if desired, as shown and have a common outlet to the atmosphere as at 11. Such passages can be multiplied as often as desirable to secure good ventilation of the building. The crypt structure can be erected on an insulator 12 of asphaltum or other suitable material to

exclude ground moisture from the crypt structure.

13 designates the outer well wall which is built of loosely laid brick, while 14 designates an inner well wall also of loosely laid brick, said inner well being of considerably smaller diameter than the outer well to form an annular space between them. In the inner well is placed an ample quantity of quick lime while in the outer well is placed a sufficient quantity of charcoal to coöperate with the lime in purifying or destroying as far as practicable the liquids flowing into the well.

Embedded in the vertical wall at the inner or permanently closed end of each tier is a carrying-off pipe 15 from which extends a short branch 16 embedded in the floor of each of the crypts. The branch pipes 16 each open in a depression or pocket 17 at the inner end of the floor of one of the crypts so that liquids which drain toward said pocket shall flow into the pipe when its end is opened. The floor of each crypt can be very slightly inclined so as to cause all liquids to flow toward the pocket. Initially each of the open ends of the branch pipes 16 is hermetically closed by an inverted test tube or bulb 18 of glass or other frangible material having a thinned wall as at 18', said tube or bulb projecting above the floor of the crypt from above the line of the thinned wall of the closure and in position to be certainly broken or removed when the casket is shoved in the crypt thus providing an opening to the branch pipe for the exit of gases and fluids generated by the decomposition of the body contained in the casket and crypt. Any suitable material, cement, for example, can be used, as at 19, to seal the frangible tube or bulb in position. The pipes 15 lead into a larger pipe 20 arranged in the floor, said larger pipe being directed to drain liquids into the inner well and also to discharge gases into the upper portion of the main well.

Leading from the main well is a pipe 21 that is extended through the floor and upward to near the roof where its upper open end is incased in a vessel 22 containing a germicide—formaldehyde for example. This pipe 21 affords a vent for any excess of gases carried to, generated in and not disposed of in the main well, and the germicide in the vessel renders such gases innocuous if any final escape.

Before inserting the casket in a crypt or catacomb the attendant is expected to break the glass tube or bulb with a rod of suitable length for the purpose but should he forget or neglect to do this the tube or bulb will certainly be destroyed by the contact of the casket therewith when the latter is pushed into its place. The opening to the crypt is then hermetically sealed with a rough slab 13 and the outer side of this is provided with a suitable marble slab or other suitable plate 23 containing appropriate or desired inscriptions respecting the deceased.

From the construction shown and described it will be observed no noxious gases, vapors or liquids can escape from the crypt containing a corpse into an open crypt or into the building. Where movable valves are used for the purpose of closing the vents 20 of the crypts my experience has been that they can not be relied on to prevent leakage.

The gases and liquids flowing into the well are first subjected to the lime and charcoal treatment and then slowly absorbed by 25 the surrounding earth.

What I claim is—

1. In a mausoleum containing a plurality of distinct crypts or catacombs, the combination of a carrying-off pipe, a branch from 30 said pipe to one of the crypts, and a frangible sealing closure within the crypt for one end of said branch pipe projecting into the crypt in position to be broken by the blow of an object inserted into the crypt from the exterior thereof to establish communication 25 between the crypt and the carrying off pipe.

2. In a mausoleum containing a plurality

of distinct crypts or catacombs, the combination of a carrying-off pipe, a branch from 40 said pipe leading into each of several of the crypts, and a closure for the ends of said branch pipes consisting of a frangible material projecting into the crypt in position to be broken by contact therewith of the inserted casket whereby communication is established between the crypt and carrying-off pipe.

3. In a mausoleum containing a plurality of distinct crypts or catacombs, the combination of a carrying-off pipe, a disinfecting 50 well into which said pipe discharges, a branch from said pipe leading into each of the several crypts, a closure for the ends of said branch pipes consisting of a hermetically sealed frangible material projecting 55 into the crypt, a pipe leading from said well to carry off surplus gases from said well and a disinfecting chamber into which said last named pipe discharges.

4. In a mausoleum containing a plurality of distinct crypts or catacombs, the combination of a carrying-off pipe, a branch from 60 said pipe leading into each of several of the crypts at the floor and a frangible closure for the end of each of said branch pipes 65 to project above the floor, said closure having its wall of annularly reduced thickness at a line below the plane of the main floor of the crypt.

JONATHAN P. COLLETT.
